UNITED STATES PATENT OFFICE.

WILLIAM J. MILLS, OF HAZLETON, PENNSYLVANIA.

LINOLEUM-CUTTER.

1,391,201.

Specification of Letters Patent. Patented Sept. 20, 1921.

Application filed July 1, 1920. Serial No. 393,287.

To all whom it may concern:

Be it known that I, WILLIAM J. MILLS, a citizen of the United States, residing at Hazleton, in the county of Luzerne and State of Pennsylvania, have invented certain new and useful Improvements in Linoleum-Cutters and the like; and I do declare the following to be a full, clear, and exact description of the invention, such as will enable others skilled in the art to which it appertains to make and use the same.

This invention relates to improvements in cutters, and it has more particular reference to a device of this class which is especially designed for cutting linoleum, oil-cloth, and the like.

One object of the invention is to generally improve upon devices of this class by producing one of extreme simplicity which is effective in operation, easy to manipulate, and inexpensive to both the manufacturer and the user.

Another object of the invention is to provide a cutter of this type which includes a stationary cutter for the thinner materials and a rotatable cutter for the heavy materials such as beaver-board and the like, the last named cutter being removed when the stationary cutter is being used.

Other objects and advantages of the invention will be apparent during the course of the following description.

In the accompanying drawings forming a part of this specification and in which like numerals are employed to designate like parts throughout the same:

Figure 1 is a side elevation of a cutter constructed in accordance with my invention.

Fig. 2 is a top plan view thereof.

Fig. 3 is a longitudinal sectional view taken on the line 3—3 of Fig. 1, looking in the direction of the arrows.

Figs. 4 and 5 are sections taken on the lines 4—4 and 5—5 respectively of Fig. 1.

Fig. 6 is a view like Fig. 1 with the rotary cutter removed.

In carrying out my invention I employ a vertically disposed plate 1, at the bottom of which and on opposite ends of which are secured by suitable means, a pair of strips of metal 2 which extend beyond the front edge of the plate. These strips constitute a base which is adapted to be moved along the floor, and for the purpose of guiding the material onto the upper surface thereof and

into engagement with the cutting edge 3 of the plate, they are tapered downwardly at their outer ends as indicated at 4. If desired, the cutting edge 3 may be curved in the manner shown to insure effective engagement thereof with the article to be cut. For the purpose of sliding the device along the floor, I provide a suitable handle 5 which is preferably secured to the rear end of the plate.

It has been before intimated that my improved device includes two separate cutters, one of which is stationary and the other of which is rotary. It is to be stated here that the stationary cutter which is the plate 1, is to be operated by hand. On the other hand, the rotary cutter yet to be described, is intended to be used when the stationary cutter is not being used. This rotary cutter is in the form of a disk 6, the same being carried by a pair of strips 7 detachably secured on opposite sides of the plate 1 adjacent the upper end thereof. These strips 7 are preferably pivoted as at 8, and are provided adjacent their rear ends with holes which align with an elongated slot 9 in the plate 1, there being a clamping bolt 10 passed through these holes and slot to permit the rotary cutter to be adjusted closer to or farther from the base of the device. This is a feature of construction because of the fact that it permits the disk 6 to be moved to most effective position for severing different thicknesses of linoleum. The rotary cutter may be operated manually, or it may be operated by a suitable motor which may be connected to it in any way. In order to permit use of the motor, it will be necessary, of course, to employ a different kind of journal from that shown, and to equip this journal with a pulley or the like.

In cutting ordinary linoleum and oil-cloth, I sometimes use the rotary cutter, and other times remove it and use the stationary cutter.

The operation of the device is as follows:

Assuming that the rotary cutter has been removed, as shown in Fig. 6, it will be seen that the tapered portion 4 of the base of the cutter is forced underneath the edge of the linoleum or other article to be cut. Then, by pushing the device forward, the linoleum will ride up and over the strips 2 and will come into engagement with the cutting edge 3 of the plate 1. The operator will then find

it advantageous to place one hand down on the linoleum and hold it steady while he pushes the cutter along with the other hand. In this manner, the linoleum may be cut on a perfectly straight line very easily and without a great deal of effort on the part of the operator. Due to the curvature of the cutting edge, the linoleum will be retained in effective engagement therewith and will be prevented from riding up as it would if the cutting edge were straight or inclined downward and toward the front end of the base. As before stated, I sometimes find it necessary and advantageous to use the rotary cutter instead of the stationary cutter. When the rotary cutter is being used, it may be adjusted to the proper position to effectively sever different thicknesses of linoleum in the manner already described. The spaced strips 2 which constitute the base of the device also form a recess for the reception of the cutting edge of the disk, that is, the extended portions of the strips serve in this manner.

From the foregoing description taken in connection with the accompanying drawings, persons skilled in the art to which this invention appertains will be enabled to obtain a clear understanding of the same, therefore, further description is deemed unnecessary.

Since probably the best results may be obtained with the construction and arrangement herein described and shown, I prefer to employ such construction. However, I wish it to be understood that various minor changes in the shape, size, and arrangement of parts may be resorted to without departing from the spirit of the invention or the scope of the subjoined claims.

I claim:

1. A cutter of the character described, comprising a blade disposed in a vertical

plane and having an operating handle at its rear end, the front end of said blade being sharpened, a pair of strips secured to opposite sides of said blade at the lower edge of the latter, said strips extending forwardly from the blade and being beveled to slide beneath the material being cut, an arm secured to the upper edge portion of said blade and extending forwardly therefrom, and a rotary cutting disk mounted on the front end of said arm, the lower edge portion of said disk being received between the front ends of said strips.

2. A cutter of the class described comprising a vertically disposed plate having its front vertical edge sharpened to provide a cutting edge and being provided adjacent its upper edge with a vertically elongated slot, strips arranged on opposite sides of said plate near the lower edge of the latter and having their lower flat faces flush with the lower edge and being extended beyond the front vertical edge of the plate and being spaced apart, the upper faces of the strips at this end being beveled so as to lift the linoleum up and cause it to ride rearwardly over these beveled faces and into engagement with one of the cutters, strips mounted on opposite sides of the upper portion of the plate and extending beyond the front edge thereof, being pivoted intermediate their ends on the plate and being provided at their rear ends with holes aligned with the aforesaid slot, a clamping bolt passing through the holes in said strip and through said slot, and a rotary disk cutter rotatably mounted between the forward extending ends of said strips and having its cutting edge received between the first named strips.

In testimony whereof I have hereunto set my hand.

WILLIAM J. MILLS.
